ARTIFICIAL LEG

Otto H. Erickson, Minneapolis, Minn.

Application August 3, 1940, Serial No. 350,960

1 Claim.

(Cl. 3-2)

My present invention relates to artificial legs and has for its object to improve the same both in respect to ease of manufacture and improved action. The invention relates particularly to artificial legs of the type required for thigh amputations, but includes also an improvement in the means for pivotally connecting the foot to the lower leg section. The major features of the invention are directed to the knee joint hinge or pivot, to means for imparting swinging movement to the lower leg section, to means for limiting the swinging movement of the lower leg section, and to a lock device whereby, under certain conditions, the lower leg section may be locked against pivotal movement in respect to the upper leg section. In addition to these improved functions the invention has for its object a structure in which the leg sections will be as free as possible from openings or external notches or joints that are liable to produce a pinching action.

A commercial form of the invention is illustrated in the accompanying drawings wherein like characters indicate like parts throughout the several views.

Referring to the drawings:

Fig. 1 is a view in front elevation showing the improved leg;

Fig. 2 is a side elevation of the improved leg with some parts broken away and some parts sectioned;

Fig. 3 is a side elevation with some parts broken away and some parts sectioned showing the knee joint structure in the same position as shown in Fig. 2;

Fig. 4 is a section taken on the line 4-4 of Fig. 1, some parts being broken away;

Fig. 5 is a section taken on the line 5-5 of Fig. 2;

Fig. 6 is a horizontal section taken on the line 6-6 of Fig. 4; and

Fig. 7 is an enlarged view showing parts found in the vicinity of the line marked 7-7 on Fig. 2, some parts being shown in full and the position of the said parts in the lower leg and foot structure being indicated by dotted lines.

The main elements of the complete leg are the upper leg section 10, the lower leg section 11, and the foot 12. The upper leg section 10, as usual, is hollowed out to form a socket to receive the upper leg amputation. The lower leg section 11 is also hollowed out to make it light, but at its lower end has a solid portion 13 to which the foot 12 is pivoted by means hereinafter to be described. The lower end of the upper leg section 10 is solid but narrowed up to form a strong segmental hub flange 14 so that it will go within the side flanges of the lower leg section 11 and is adapted to be pivoted or hingedly connected to said lower leg section.

The leg sections and the foot may be made of any suitable material, but preferably are made of wood hollowed or dug out to form strong but comparatively light shells.

5 The knee joint pivot, between the said hub flange 14 and the sides of the lower leg section 11, is made by a metal sleeve or bushing 15 and a metallic hinge bolt 16. The sleeve 15 is tightly driven into the hole bored in the hub flange 14 and it is further anchored therein by suitable means such as nut-equipped eye bolts 17, applied as best shown in Figs. 4 and 5, with the nuts of the said bolts countersunk into recesses of the said hub flange. The hinge bolt 16 is passed through the sleeve or bushing 15 with clearance so that wire-like rollers 18 are interposed between said bolt and sleeve. The ends of the bolts 16 are passed through the ends of metallic straps 19 that are riveted or otherwise rigidly secured to 10 the sides of the lower leg section 11. At one end hinge bolt 16 is shown as provided with a head that has threaded engagement with the adjacent strap 19, but at its other end said bolt is shown as provided with a head-forming screw 20 that 15 clamps the opposite hinge strap 19. Also, preferably, and as shown, the bolt 16 is formed with oil-containing grooves 21 adapted to contain a limited amount of oil or grease for delivery to the rollers 18. On the ends of the knee hinge 20 bolt 16, between the upper ends of the straps 19 and the ends of the sleeve 15, are loosely journaled small sheaves or grooved wheels 22.

The elements of the preferred form of the knee hinge connection between the upper and lower leg sections have now been described. For limiting the pivotal or forward and rearward swinging movement of the lower leg section in respect to the upper leg section, I provide an extremely simple and highly efficient device which, in its 25 preferred arrangement, is accomplished by providing the hub flange 14 with a segmental slot 23 that is concentric to the axis of the hinge bolt 16. For cooperation with the slot 23, I employ a simple stop bolt or rod 24 that extends transversely through the slot 23 and through the hinge straps 19, and is anchored to the latter. This stop bolt may be applied in various ways, but preferably and as shown, at one end is provided with a head 25 that has threaded engagement with the adjacent strap 19, and at its other end is provided with a head-forming screw 26 that engages the other strap 19. With this arrangement, both the hinge bolts 16 and the stop bolt or rod 24 are anchored to the metallic straps 19, which in turn are rigidly secured to the lower leg section. Journaled on the ends of the stop bolt 24, between the straps 19 and the sides of the hub flange 14, are small sheaves or grooved wheels 27.

30 35 40 45 50 55 60 Legs of the kind described are customarily

carried in part from the shoulders of the wearer by suspenders made up of shoulder straps, not shown, and cords 28. These cords are brought from the outer sides of the upper leg section through guide slots 29 and are passed against the front faces of the sheaves 22 and under and around the sheaves 27, as best shown in Fig. 3. The suspender structure usually includes an elastic element or, at any rate, is so designed that there will be an upward tension maintained on the suspending cords 28; and this upward strain or tension will tend to impart a forward swinging movement to the lower leg section, or in the walking action, the foot is released from pressure on the ground. That this action will take place will appear evident by noting in Fig. 3, for example, the fact that the cords are brought rearward and back of the axis of the knee joint pivot.

The forward and rearward movements of the lower leg section in respect to the upper leg section is limited by engagement of the stop pin or bolt 24 with the extreme ends of the slot 23. To cushion the movements of the lower leg section, leather or other pliable buffers 23' are preferably inserted at the ends of the slot 23. In fact, the ends of the slot 23 or the buffers 23' form limiting stops that are offset from the axis of the knee joint and are circumferentially spaced. The segmental slot, however, in addition to performing the function of a stop means, serves as a sort of guide device for giving the leg structure lateral stability. It will be noted that the sides of the hub flanges 14 quite closely engage the inner faces of the sheaves 27 and keep the latter pressed against the metallic hinge straps 19.

The sheaves 22 and 27, and especially the latter, permit the straps 28 that freedom of endwise movement that is required to prevent slipping of the shoulder straps on the wearer when, for example, the person wearing the leg sits down and permits the lower leg section to move pivotally backward or toward a position indicated by dotted lines on Fig. 4.

Some persons wearing legs of this general character find it necessary or desirable to walk with stiff knee joint; hence, I provide a lock device preferably in the nature of a sliding lock bolt which may be readily moved from inoperative position to operative position to lock the leg structure against movement at the knee joint. This device, as shown in the drawings, involves a lock bolt 30 mounted to slide vertically through the hub flange 14 from an inoperative position shown by dotted lines on Fig. 4, into an operative position shown by full lines, and in which latter position, the lower end of said lock bolt will engage back of the stop bolt or rod 24 and lock the knee joint against movement. Lock bolt 30, in the particular structure illustrated, is provided with a laterally turned end that works through a slot 31 in the back of the leg and, as shown, is provided with a head 32 affording a finger piece. In many and probably most of the legs manufactured in accordance with the major features of this invention, this lock bolt will not be applied, but if applied, it may be readily set and held frictionally or otherwise in a retracted or inoperative position.

The foot structure, except for a feature hereinafter noted, is or may be substantially the arrangement disclosed in my prior Patent No. 1,405,191. As shown in the drawings Figs. 2 and

7, the ankle joint pivot involves a sleeve 33 that is set into or against the solid portion 13 of the lower leg section 11 and is anchored thereto by nut-equipped bolt-like extensions 34. Working within the sleeve 33 is a shaft 35 between which and the sleeve 33 wire-like rollers 36 are preferably interposed. Working through segmental slots 37 in the sleeve 33, and having threaded engagement with the shaft 35 and projecting radially therefrom, are trunnions 38 provided with stud-like projections 39 equipped at their lower ends with adjustable nuts 40. Studs 39 are passed freely through clamping bars 41 and 42. By reference particularly to Fig. 2 it will be noted that when applied to the foot 12, the studs 39 are passed through a web 12' in the heel of the foot and that when nuts 40 are tightened, the bars 41 and 42 will be clamped tightly against the web 12'. The nuts 40 and lower bars 42 are countersunk into the hole of the foot. With this arrangement the nuts 40 can be tightened to any desired extent without in any way varying the frictional contact between the sleeve 33 and the shaft 35. As further shown in Fig. 2, the numeral 43 indicates a heel spring applied between the heel of the foot and the solid lower end of the lower leg section. The numeral 44 indicates a stop for limiting the hinge movement of the foot under the action of spring 43. These elements 43 and 44, however, are not per se features of the present invention.

This improved leg has been put into commercial use and has been found highly efficient for the purposes had in view. It has few parts and in fact has no parts that require frequent adjustment. The stop elements for limiting the movements of the lower leg section in respect to the upper leg section are solidly connected one to the upper leg section, and the other to the lower and require no adjustments if once properly designed.

What is believed to be the simplest and best structure is illustrated in the accompanying drawings, but it will be understood that various modifications may be made within the scope of the invention herein disclosed and claimed.

What I claim is:

An artificial leg comprising lower and upper leg sections, metallic hinge straps secured to the upper side portions of said lower leg section, said upper leg section having a segmental hub flange located between the upper ends of said hinge straps, a knee hinge bolt extended through the hub flange of said upper section and at its ends anchored to the upper portions of said hinge straps, a stop bolt located directly below said knee joint hinge bolt and at its ends anchored to said hinge straps, said hub flange having circumferentially spaced stop elements engageable with said stop bolt to limit the swinging movements of said lower leg section in respect to said upper leg section, and shoulder straps extended in front of said knee hinge bolt and around and under said stop bolt, said shoulder straps, under upward tension, serving to cause said lower leg section to swing forward in respect to said upper leg section, in further combination with a lock bolt mounted in the upper leg section for movement through the hub flange thereof into a position to engage said stop bolt and lock the lower leg section against pivotal movement in respect to the lower leg section.

OTTO H. ERICKSON.
